WATCH CLEANING MACHINE

Herman F. Pabst, Huntington Park, Calif.

Application August 11, 1937, Serial No. 158,458

5 Claims. (Cl. 141—1)

This invention relates to the horological art and particularly to apparatus for cleaning watch parts and the like.

It is an object of my invention to provide a machine for cleaning watch parts and the like, which from the time the watch parts are committed thereto will be self-operating until the process of cleaning these watch parts has been completely finished.

It is a further object of my invention to provide such a machine which is simple in construction, inexpensive to build, which may be operated at a low cost, and which will be long lived.

The manner of accomplishing the foregoing objects as well as further objects and advantages will be made manifest in the following description taken in connection with the accompanying drawings in which:

Fig. 1 is a plan view of a preferred embodiment of my invention;

Fig. 2 is a vertical sectional view taken on the line 2—2 of Fig. 1;

Fig. 3 is a horizontal sectional view taken on the line 3—3 of Fig. 2;

Fig. 4 is a fragmentary vertical sectional view taken on the line 4—4 of Fig. 3;

Fig. 5 is a fragmentary vertical sectional view taken on the line 5—5 of Fig. 2;

Fig. 6 is a fragmentary detailed sectional view taken on the line 6—6 of Fig. 2;

Fig. 7 is a diagram of electrical wiring of the machine illustrated in the other views.

I shall now refer specifically to the drawings in which a machine 10 comprising the preferred embodiment of my invention is illustrated. This machine has a base frame 11 which includes a floor 12 having legs 13 and a flange 14 from which flange a wall 15 extends vertically upward. Secured to the upper edge of the wall 15 and supported thereon is a frame ring 16 having an opening 17 in the center thereof and a vertical bearing 18 which is in vertical alignment with a bearing 19 provided on the floor 12 (see Figs. 3 and 4). The floor 12 also has bearings 20 and 21, the axis of which lies in the same plane as the axis of the bearings 18 and 19. Also provided in the floor 12 are bearings 25, 26, 27, 28 and 29 (see Figs. 2, 3 and 4).

The floor 12 has a wall 30 formed integral therewith and which extends downwardly therefrom just beneath the bearings 21 and 26, the wall 30 being enclosed within a flat portion 31 of the wall 15. Extending outwardly from the wall 30 is a platform 32 on which is provided a socket 33, the lower end of this serving coor-

dinate with the legs 13 to support the machine 10.

Journalled in bearing 25 is a vertical table shaft 40 which has a turned-down extension 41 at its lower end and on the upper end of which is mounted an intermittently rotatable table 42. The table 42 includes a hub 43 which is in the form of a Geneva wheel having radial slots 44 (see Fig. 3) upon which is secured a table deck plate 45. This deck plate rests very close to or slidingly upon the frame ring 16 and is provided with a series of sockets 46. One of the sockets 46 is adapted to hold a dryer 47, the deck plate 45 having a hole 48 therein beneath the dryer 47. Just above the hole 48 is a ring of asbestos 50 which supports an electric heating element 51 (see Figs. 2, 5 and 6). The dryer 47 also includes a tubular wall 52 which fits within its socket 46 and rests on ring 50.

Mounted on the base floor 12 is an electric motor 55 driving a blower 56, the discharge of which is connected to a tube 57 leading to a nozzle 58. This nozzle is located so as to direct air upwardly, and is disposed the same radial distance from the axis of the shaft 40 as the hole 48 so that this hole may be brought directly over the nozzle 58 as shown in Fig. 2.

The other sockets 46 support jars 60, 61 and 62 which have vertical flanges 63 extending inwardly from the walls thereof and are adapted to contain liquids to be employed in the cleaning of watch parts.

Mounted on a lower portion 70 of the floor 12 is a drive motor 71 having a shaft 72 which carries a worm 73 and the end of which shaft is journalled in the bearing 29 (see Fig. 3). Journalled in bearings 27 and 28 is a shaft 74 having a worm gear 75 which meshes with the worm 73 so as to transmit rotary motion from the shaft 72 to the shaft 74. Also provided on the shaft 74 is a worm 76 which meshes with a worm gear 77 provided on a vertical shaft 78, the opposite ends of which are journalled in bearings 18 and 19. Fixed on the shaft 78 above gear 77 is an arm 80 having a roller 81 which is adapted to travel in slots 44 of the table hub 43 in a manner and for a purpose to be described hereinafter. Fixed on the shaft 78 below the gear 77 is a mitre gear 85 which meshes with a mitre gear 86 provided on the inner end of a shaft 87 which is journalled in the bearings 20 and 21 (see Figs. 3 and 4).

Fixed on the opposite end of the shaft 87 is an intermittent drive gear 88 having toothed sectors 89, and sectors 90 which are bare of teeth. Journalled in bearing 26 is a crank shaft 91 hav-

ing a switch cam 82 fixed to its inner end and a gear 83 and crank arm 84 fixed to its outer end. Gear 83 has toothed segments 83a and smooth dwells 83b. The wall 31 has an opening 5 surrounding the hub of gear 83 and lies between this gear and the crank arm 84. The gear 83 is in radial alignment with the gear 88 and when a sector 89 is opposite the gear 83, a segment 83a of the latter meshes with this sector. When a 10 sector 90 is opposite the gear 83 however, this sector extends into a dwell 83b in gear 83 which holds the latter from rotating until engaged by the next sector 89.

Mounted in the socket 33 is a vertical slide 15 shaft 85 on which is splined for vertical sliding movement a sleeve 86 having a shaft 87 extending horizontally therefrom inwardly towards the table 42. Pivotally mounted at its lower end on the crank 44 and at its upper end on the shaft 20 87 is a pitman 88. The inner end of the shaft 87 supports an electric motor 89, the shaft 100 of which has a downward extension 101 which is adapted to support basket 102 containing watch parts and to transmit rotary motion from the 25 shaft 100 to the basket 102 when the motor 89 is energized.

Mounted on the floor 12 is a switch 105 (see Fig. 5) for controlling the motor 89, said switch being actuated by a roller arm 106 which follows the periphery of the cam 82 as the gear 83 rotates.

Mounted on the bottom of the floor 12 is a rotary distributing switch 108 which includes a hub 109 of insulating material, the latter being 35 fixed upon the downward extension 41 of the shaft 40. The hub 109 of switch 108 has ring conductors 110 and 111 and segmental conductors 112, 113, 114 and 115. As shown in Fig. 7, the conductor ring 110 is electrically connected to the 40 segmental conductors 113 and 114 and the ring 111 is connected to the segmental conductor 115. Bearing against the cylindrical outer surface of the switch hub 109 in the same planes as the conductors 110, 112, 113, 114 and 111 respectively, are brushes 115a, 116, 117, 118 and 119 (see 45 Figs. 2 and 7).

As indicated in the wiring diagram of Fig. 7, electricity is received from the generator G and transmitted continuously to the main drive motor 50 71 when a main switch 120 is closed. Electricity is also transmitted from the generator G to the basket rotating motor 99 whenever the switch 105 is closed. The latter takes place whenever the low point or dwell of the cam 82 is rotated 55 with the gear 83 so as to come opposite the roller arm 106 of the switch 108. The conductor ring 111 and segments 114 and 115 are provided to control the speed of the basket rotating motor 99. The segment 114 being electrically connected to 60 the ring 110 causes the motor 99 to run at full speed when the contact 118 rides on the segment 114. When the contact 118 passes from the segment 114 onto the segment 115 the current is reduced by a suitable resistance R to cause the motor 99 to run at slow speed when extending down 65 into the jar 60.

As also shown by the wiring diagram of Fig. 7, the rotary switch 108 controls the passage of electricity from the generator G to the heater 51 of the dryer 47 and to the motor 55 of this dryer. Opposite terminals of heater 51 are connected by suitable conductors with the segments 110 and 70 112 of the switch 108, these conductors being diagrammatically shown in Figs. 2 and 7. In other words, the heater 51 is energized only when the

rotation of the hub 109 of the switch 108 brings the segment 112 into contact with the brush 116 and the blower motor 55 is only energized when the rotation of the hub 109 brings the segment 113 thereon into contact with the brush 117, as 5 will be readily understood by those skilled in the art.

Operation

The preferred manner in which the machine 10 10 of my invention operates is as follows:

The switch 120 is always shut off at the conclusion of a watch parts cleaning operation with the crank 84 turned so as to lift the pitman 88 upwardly and thus hold the basket 102 entirely 15 above the level of the upper edges of the jars 60, 61 and 62 and the dryer 47 and with the table 42 so positioned that when the crank 84 again turns to lower the basket 102, the latter will be extended downwardly into the jar 60. Before 20 starting the cleaning operation, the jar 60 is partly filled with a quantity of cleaning liquid, the jar 61 is partly filled with a body of rinse liquid and the jar 62 is partly filled with a second body of rinse liquid.

The basket 102 is now removed from the member 101, the watch parts to be cleaned are placed in the basket, and the basket is reapplied to the member 101 as shown in Fig. 2, although this basket is still suspended above the upper end of the jar 60. The main switch 120 is now closed 30 starting the main drive motor 71, which, until the end of the cleaning operation about to be described, continuously rotates shafts 72, 74, 78 and 35 87.

When the switch 120 is thus thrown in, the gears 88 and 83 are related to each other approximately as shown in Fig. 5, and the energizing of the motor 71 results in the operative meshing of one sector 89 of the gear 88 with the gear 83, so as to rotate the latter and swing the crank arm 40 84 downwardly, thus lowering the basket 102 into the jar 60 which is disposed therebeneath. When this takes place, the arm 80 (see Figs. 3 and 4) is swinging in the direction of the arrow 125 and carrying the roller 81 on the end of this arm out 45 of one of the slots 44 of the Geneva gear 43 so as to leave the table 42 standing still.

As the basket 102 reaches its lowermost position, the gear 88 has rotated to the point where 50 the teeth of the sector 89 disengage the teeth of the gear 83, this causing the rotation of the gear 83 to cease with the crank arm 84 extending downwardly. When this occurs, the cam 82 has rotated so that the low point in the periphery thereof is opposite the roller arm 106 causing the latter to swing inwardly and close the switch 105, this energizing the motor 99 through resistance R, ring 111 and sector 115 (see Fig. 7) so as to 55 rotate the basket 102 at a relatively slow rate of speed.

As the jar 60 in which the basket is now disposed is filled with cleaning liquid to a level above the upper end of the basket, the basket and the watch parts contained therein are submerged in 60 this liquid, as the basket is rotated, thereby dissolving and washing from said watch parts all accumulations of dirt, grease, etc. The baffle fins 63 prevent the entire body of liquid in the jar from rotating with the basket 102 and keep 70 the basket submerged in the liquid while the basket is rotating.

The continuous operation of the motor 71 causes the arm 80 to swing around in the direction of the arrow 125 to where the roller 81 at 75

the end thereof approaches the mouth of the next slot 44 on the Geneva wheel 43. Before roller 81 enters this slot, however, the gear 88 has been rotated approximately a quarter revolution since it previously disengaged the gear 93, this bringing the teeth of the second sector 89 into mesh with the gear 93 and rotating the crank arm 94 so as to lift the basket 102 out of and entirely above the jar 60. Before the basket

10 reaches the upper end of jar 60, the rotation of the motor 99 is stopped by the high portion of the cam 92 coming opposite the roller arm 106 of the switch 105 controlling this motor, as shown in Fig. 5. The basket 102 is thus not rotating when 15 it is removed from the jar 60. This prevents liquid being thrown from the basket 102 by centrifugal force which would take place if the basket was allowed to continue rotating.

As the basket 102 is thus lifted from the jar 20 60, the roller 81 moves into the next slot 44 of the Geneva wheel 43 and rotates the table 42 just a sufficient distance to bring the jar 61 directly beneath the basket 102. As will be recalled, this jar contains the first rinse solution, and immediately after this jar has thus been positioned beneath the basket 102, the latter is lowered into the rinse solution in this jar and the rotation of the basket by the motor 99 is started by the switch 105. The motor 99 now rotates at full speed because it is energized through the ring 110 and sector 114 which cuts out the resistance R. Only while the watch parts are being cleaned in jar 60 is the speed of motor 99 decreased, this being preferable for maximum cleaning efficiency 35 of the cleaning solution in jar 60.

In the same manner as the basket 102 was rotated for a substantial period in the cleaning solution in the jar 60, it is now allowed to continue to rotate in the jar 61, after which it is 40 lifted up in the same manner as previously described, the table 42 is again rotated to bring the jar 62 in position beneath the basket 102 and the latter is again lowered, this time within the jar 62 which contains a second rinse solution 45 and in which the basket is rotated again for a given period at high velocity by the motor 99. At the conclusion of the period during which the basket 102 is rotated in jar 62, the basket is lifted upward automatically from this jar, the table 42 is rotated to bring the dryer 47 into 50 position beneath the basket and the latter is now lowered into this dryer and rotated for a period of the same length as it was rotated previously in each of the jars 60, 61 and 62.

55 When the jar 62 was first brought into position beneath the basket 102, the switch 108 caused contact to be made between the conductor 112 and the brush 116 so as to energize the heater 51 to cause this to heat up the dryer 47, so that 60 when the latter is brought beneath the basket 102, as already described, it is hot and ready to dry the watch parts in the basket. As the dryer 47 moves into position beneath the basket, the segment 113 on the switch rotor 109 comes into 65 engagement with the brush 117 and energizes the motor 55 so as to drive the blower 58 and cause a blast of air to be expelled upwardly from the nozzle 58 through the hole 48 and the heating element 51 against the basket 102, which now is 70 being lowered into its lowermost position in the dryer and is being rapidly rotated by the motor 99.

The switch 120 has a handle 150 which when turned to the full line position in Fig. 1, turns 75 the switch 120 on and when turned to the broken

line position 151 in that figure turns the switch 120 off. The table 42 is provided with a dog 152 which is so positioned thereon that after the basket has been rotated for its usual period in the dryer 47 and then lifted upwardly, and the table rotated by the engagement of the roller 81 with the Geneva wheel 43 the dog 152 engages the handle 150 of the switch 120 so as to shut off this switch and de-energize the motor 71 10 when the table is rotated to a position in which the dryer 47 and the jar 60 are spaced equally on opposite sides of the elevated basket 102. When the table 42 is thus stopped, the dog 152 is approximately in its dotted line position 153 (see Fig. 1). 15

The watch parts which are now completely cleaned and dried, may be removed from the basket 102 and another set of watch parts placed in this basket in order to clean these in the machine 10. To cause the machine 10 to go through another complete cycle of operations as above described, the operator merely turns the handle 150 of the switch 120 from its dotted line position 151 to its full line position as shown in Fig. 1. 20

For convenience the basket 102 and motor 99 25 may be considered as a watch part dousing unit.

What I claim is:

1. In a machine for cleaning watch parts and the like, the combination of: a dousing unit including a basket, for containing watch parts to be cleaned, and a motor for rapidly rotating said basket; power means for reciprocating said unit between raised and lowered positions, said means having lost motion while said unit is in said lowered position; container means providing a 30 series of treating chambers; means actuated by said power means to produce relative horizontal movement between said container means and said unit while said unit is in raised position to bring a given one of said chambers into vertical 35 alignment with said basket; and switch means for controlling said motor, said switch means being responsive to said power means to energize said motor coordinately with said lowering of 40 said unit. 45

2. In a machine for cleaning watch parts and the like, the combination of: a dousing unit including a basket for containing watch parts to be cleaned and a motor for rapidly rotating said basket about a vertical axis; container means 50 providing a series of treating chambers; power means for automatically causing relative vertical movement between said unit and said container means to cause a minimum spaced relation there-between in which said basket is disposed in one 55 of said chambers and then to restore a maximum spaced relation in which said basket is located out of said chamber; mechanism actuated by said power means in timely relation with said relative vertical movement to produce relative 60 horizontal movement between said container means and said unit during said maximum spaced relation to bring another given one of said chambers into vertical alignment with said basket; and switch means actuated by said power 65 means in timely relation with said relative vertical movement to energize said motor when said basket is disposed in one of said chambers and to deenergize said motor when said basket is removed by said relative vertical movement from 70 said chamber. 75

3. In a machine for cleaning watch parts and the like, the combination of: a dousing unit including a basket for containing watch parts to be cleaned and means for rapidly rotating said 75

basket about a vertical axis; container means providing a series of treating chambers; power means for automatically causing relative vertical movement between said unit and said container means to cause a minimum spaced relation therebetween in which said basket is disposed in one of said chambers and then to restore a maximum spaced relation in which said basket is located out of said chamber; mechanism actuated by said power means in timely relation with said relative vertical movement to produce relative horizontal movement between said container means and said unit during said maximum spaced relation to bring another given one of said chambers into vertical alignment with said basket, said power means being continuously operative when once started to cause said basket to be disposed as aforesaid consecutively in all of said treating chambers; means for starting and stopping the operation of said power means; and means responsive to said mechanism and actuating said last aforementioned means to stop said power means after said basket has been caused to be disposed consecutively in all of said chambers of said container means.

5. In a machine for cleaning watch parts and the like, the combination of: a dousing unit including a basket for containing watch parts to be cleaned and means for rapidly rotating said basket about a vertical axis; container means providing a series of treating chambers; power means for automatically causing relative vertical movement between said unit and said container means to cause a minimum spaced relation therebetween, in which said basket is disposed in one of said chambers, and then to restore a maximum spaced relation in which said basket is located out of said chamber; mechanism actuated by said power means in timely relation with said relative vertical movement to produce relative horizontal movement between said container means and said unit during said maximum spaced relation to bring another given one of said chambers into vertical alignment with said basket, said power means being continuously operative when once started to cause said basket to be disposed as aforesaid consecutively in all of said treating chambers; and means operated in timely relation with said mechanism for varying the speed with which said basket is rotated in said different chambers.

4. In a machine for cleaning watch parts and the like, the combination of: a dousing unit including a basket for containing watch parts to be cleaned and means for rapidly rotating said basket about a vertical axis; container means providing a series of treating chambers; power means for automatically causing relative vertical movement between said unit and said container means to cause a minimum spaced relation therebetween in which said basket is disposed in one of said chambers and then to restore a maximum spaced relation in which said basket is located out of said chamber; mechanism actuated by said power means in timely relation with said relative vertical movement to produce relative

horizontal movement between said container means and said unit during said maximum spaced relation to bring another given one of said chambers into vertical alignment with said basket, said power means being continuously operative when once started to cause said basket to be disposed as aforesaid consecutively in all of said treating chambers; means for starting and stopping the operation of said power means; and means responsive to said mechanism and actuating said last aforementioned means to stop said power means after said basket has been caused to be disposed consecutively in all of said chambers of said container means.

5. In a machine for cleaning watch parts and the like, the combination of: a dousing unit including a basket for containing watch parts to be cleaned and means for rapidly rotating said basket about a vertical axis; container means providing a series of treating chambers; power means for automatically causing relative vertical movement between said unit and said container means to cause a minimum spaced relation therebetween, in which said basket is disposed in one of said chambers, and then to restore a maximum spaced relation in which said basket is located out of said chamber; mechanism actuated by said power means in timely relation with said relative vertical movement to produce relative horizontal movement between said container means and said unit during said maximum spaced relation to bring another given one of said chambers into vertical alignment with said basket, said power means being continuously operative when once started to cause said basket to be disposed as aforesaid consecutively in all of said treating chambers; and means operated in timely relation with said mechanism for varying the speed with which said basket is rotated in said different chambers.

HERMAN F. PABST.
